UNITED STATES PATENT OFFICE.

HENRY F. DIERCKS, OF ALGONQUIN, ILLINOIS.

STUCCO FOUNDATION FOR BUILDING-WALLS.

1,370,095.

Specification of Letters Patent.

Patented Mar. 1, 1921.

Application filed February 9, 1920. Serial No. 357,453.

To all whom it may concern:

Be it known that I, HENRY F. DIERCKS, a citizen of the United States, and a resident of Algonquin, in the county of McHenry and

5 State of Illinois, have invented certain new and useful Improvements in Stucco Foundations for Building-Walls; and I do hereby declare that the following is a full, clear, and exact description thereof, reference being had to the accompanying drawings, and to the characters of reference marked thereon, which form a part of this specification.

This invention relates to improvements in exterior face finishing for building walls 15 which comprises an outer cementitious material and an inner structure comprising part of the wall which is formed to provide an anchor for the finishing face, the construction of the inner part of the wall having known under cut grooves or recesses to receive portions of the cementitious material in an interlocking fashion, to hold the facing layer thereon. These wall finishings are usually known by the term stucco finish.

25 The invention relates more particularly to a stucco wall finish of this character which is adapted to be applied to old buildings, and when applied to the wall the markings on the finished surface may be of any suitable character.

The principal object of the invention is to provide a peculiar form of lath and the manner of its use in an ordinary overlapped weatherboard siding wall which is the lath 35 being adapted to be applied to the exposed or weather faces of the overlapped sidings of a wall of an old building, so as to produce a plain or substantially plain foundation for the stucco or finishing layer, and also 40 provide in a novel way interlocking grooves or recesses in the wall structure by which to anchor the stucco finishing layer, which latter, as before stated, may be exteriorly finished or designed to suit the artistic taste 45 of the builder.

A further object of the invention is to so adapt a novel form of lathing to the overlapped covering members of a building wall as to produce in a very simple way a plain 50 face to receive the stucco material, and undercut grooves to interlock or anchor the material with the wall structure.

Other objects of the invention are to improve, simplify, and reduce the cost of the 55 application of a stucco facing finish for old buildings, and the invention consists in the

combination and arrangements of the parts shown in the drawings and described in the specification, and is pointed out in the appended claims.

60 In the drawings is shown one embodiment of my invention wherein—

Figure 1 is a fragmentary face view showing in different planes the old overlapping siding of a building wall, the lathing applied thereto, and the finished wall.

Fig. 2 is a vertical section of a wall equipped with my improvement.

Fig. 3 is a transverse section of a board showing the manner in which the lathing 70 may be cut therefrom.

Fig. 4 is a perspective view of an end portion of one of the laths.

As shown in Fig. 1, 10 designates a studding of a building wall, and 11, 11 designate 75 a familiar form of overlapped siding that is nailed to the studding.

12, 12 designate lath strips or lathing which is applied and nailed to the outer faces of the exposed portions of the overlapped 80 siding. The said lath strips 12 are each made wider at one edge than at its other, being thus tapered so that when the narrower edge 13 of a lath strip is applied over the butt or wider edge of a siding board 11, 85 with said narrower edge substantially flush with the square wider edge of said siding board. The angle of the taper of the lathing strip is such as to cause the outer face of the lathing strip, when so applied, to be substantially parallel to the plane of the studding 10, and with the outer faces of the lathing strips disposed in the same plane. The said lathing strips 12 are of less width than the weather exposed faces of the siding 95 boards so that when applied and nailed to the siding boards there is produced between the lower wider edges 14, 14 of the lathing strips and the adjacent butt edges of the siding boards horizontal grooves 15. The angle 100 of transverse taper of the lathing strips 12 is such that when a number thereof are applied to adjacent siding boards the outer faces of the said lathing strips of the compound wall structure thus formed lie in a 105 plane substantially parallel to the plane of the adjacent faces of the studding 10, interrupted only by the grooves 15.

16 designates the finishing face of the wall which is made of plastic, cementitious, or 110 so-called stucco material that is laid in proper thickness over the compound wall

structure formed by the overlapped siding boards and the overlapped lathing strips, and the grooves 15 receive a portion of this material to form anchoring ribs 17 that interlock with the walls of the grooves 15 to hold the finishing surface of the stucco wall in place. It is desirable, in order to produce and maintain a good interlocking connection between the facing or stucco layer 16 and the wall structure described that, at least, one of the walls of each groove 15 be beveled to give an undercut effect to the groove, and for this purpose the wider side margins 14 of the lathing strips are so beveled. Fig. 3 indicates a method by which these tapered and beveled strips may be readily produced from a rectangular strip or board.

In practice, a piece of lumber of proper dimensions may be sawed into a number of parts of the dimension shown in Fig. 3. The first cut of the saw will be at an angle to the plane of the board to produce an angle edge 14, which appears at the thicker side of the lath strip. To produce this taper, the board may be applied to the saw on a table that is tilted at the proper angle. Thereafter the table will remain at this angle, while successive strips are sawed from the board, each strip being of the cross section shown in Fig. 3. Thereafter the strip is adjusted on the table so as to rip it along the diagonal line 18, shown in Fig. 3, which extends from one side margin to the other of the strip so as to produce two lathing strips 12 of the triangular cross section indicated in Fig. 3 and shown in Figs. 2 and 4, the finished lathing strip being tapered from edge to edge, so as to fit the taper of the siding boards and angled or beveled along its wider edge 14 to produce the undercut effect in the groove 15. The stucco layer 16 of the wall may be marked or decorated before the plastic material thereof hardens so as to simulate a pebble dash or concrete wall or to otherwise ornament the facing surface of the wall.

From what has been hereinbefore stated, it will be apparent that the ordinary weather board wall of an old building, may, by the very simple and inexpensive method disclosed, be converted into a wall having a stucco facing that may be made to closely resemble a block wall or concrete block wall or may be given any other ornamentation desired. It will also be observed that the wall finish may be produced by the use of inexpensive materials, the wider or butt edges of the old siding boards constituting parts of the grooves 15 to thereby hold the finishing layers 16 in place. It will also be observed that this effect is produced without greatly increasing the thickness of the wall structure as a whole inasmuch as the outer surfaces of the lathing strips do not extend substantially beyond the outermost corners of

the butt edges of the siding boards. Practically, therefore, the only thickness added to the wall structure is that due to the thickness of the finishing layer 16 itself.

It will, furthermore, be observed that the structure disclosed, while strong and compact, is a durable one, readily applied, and very economical in respect of material and labor to construct it. In practice, the said lathing strips may be made of any suitable length, as, for instance, the length of an ordinary wall lath and the width of the strips will depend on the weather exposed faces of the siding boards 11.

I claim as my invention:

1. A substantially wedge-shaped lath strip adapted for application to and coöperation with wall weather-boarding arranged in overlapped relation, to form retaining grooves therebetween, said strip being provided with a face adapted to be positioned upon said weather-boarding, an outer face, and a third face which is narrower than either of the two other faces, substantially as described.

2. The combination with a building wall including elements arranged in overlapping relation, each having an outer face and a downwardly facing edge at an angle to said face, of a strip positioned upon the outer face of each element and provided with an upwardly facing edge which is opposed to and spaced from the downwardly facing edge of the element above, whereby to form a groove therebetween, and cementitious material covering said elements and strips and filling said grooves.

3. The combination with a building wall including elements arranged in overlapping and inclined relation, each presenting an outer face and a downwardly facing edge lying in a plane substantially at right angles to said face, of a strip having an inner face secured to the inclined outer face of each element and provided with an upwardly facing edge lying in a plane at an obtuse angle to the inner face of the strip and opposed to and spaced from the downwardly facing edge of the element above, whereby to form, between said strip and element, a groove which is wider at the bottom than at the top, and cementitious material covering said elements and strip and filling said grooves.

4. The combination with a building wall including elements arranged in overlapping relation, each presenting an inclined outer face and a downwardly facing edge at an angle thereto, of a strip positioned upon each of said elements and presenting an outer face, and an edge which is opposed to and spaced from the exposed edge of the adjacent element, the edge of said strip forming, with the outer face thereof, an angle which is less than the angle formed

between the outer face and downwardly facing edge of said elements, and cementitious material covering said elements and strips and filling the spaces therebetween.

- 5 5. The combination with a building wall including a support and elements arranged in overlapping relation on said support and presenting an outer face inclined with respect to the plane of said support, and a
- 10 downwardly facing edge at an angle to said outer face, of a strip of substantially triangular cross-sectional configuration positioned upon each element and provided with an edge which is opposed to and spaced
- 15 from the downwardly facing edge of the adjacent element, the inner face of said strip conforming to the outer face of the element upon which it rests, while the outer face of the strip is in substantial parallelism to the

plane of said support, and cementitious material covering said elements and strips and filling the spaces therebetween, substantially as described. 20

6. The method of providing a finish for a wall made up of weather-boarding arranged in overlapping relation on a support, which consists in positioning lathing strips on said weather-boarding so as to form sidewise opening grooves between the boarding and strips, and thereafter applying cementitious material to said wall to cover the weather-boarding and strips and fill said grooves, substantially as described. 25 30

In witness whereof I claim the foregoing as my invention, I hereunto append my signature at Algonquin, Illinois, this 6th day of February, 1920. 35

HENRY F. DIERCKS.
